METHOD AND APPARATUS FOR ODORIZING
LIQUEFIED GASWalter C. Dayhuff, Whittier, Calif., assignor to
Standard Oil Company of California, San
Francisco, Calif., a corporation of Delaware

Application September 24, 1941, Serial No. 412,138

10 Claims. (Cl. 62—1)

This invention relates to a method and apparatus for controlling the odorization of liquefied gas which is stored under pressure and then vaporized to gaseous form for use, and particularly to such a method and apparatus for a system to which are connected successive containers of liquefied hydrocarbon gas which has been odorized with a material less volatile than the particular hydrocarbons present.

Because of the so-called differential vaporization of the lighter fractions in a mixture of liquefied gas and an odorant which is less volatile than the liquefied gas, the usual procedure of evaporating the mixture from a liquid surface and permitting it to pass freely out of the tank or cylinder outlet results in considerable variation in odorant intensity of the gas. This is due to the well-known tendency of the lighter fractions or components to evaporate from the liquid surface at a greater rate than the heavier components, the latter including the less volatile odorant. Effective odorization of gas representing the first few per cent of such a liquid mixture withdrawn from a tank or cylinder can usually be accomplished only by having present in the liquid such a high concentration of the less volatile odorizing medium that the gas representing the last few per cent of the liquid mixture in the tank or cylinder is considerably over-odorized. This results in an odor nuisance that is well recognized in this art.

The United States Bureau of Mines has extensively investigated gas odorization and has substantially standardized an odor intensity scale which is related to the degree of explosibility of a mixture of gas and air in a room. In the United States Bureau of Mines Report of Investigations R. I. 2979, "Odor Intensity and Symptoms Produced by Commercial Propane, Butane, Pentane, Hexane, and Heptane Vapor," a scale of odor is given which is quoted below:

Numerical degree	Intensity	Description
0.....	No odor	No detectable odor.
1.....	Very faint	Minimum but positively perceptible.
2.....	Faint	Weak odor, readily perceptible.
3.....	Easily noticeable	Moderate intensity.
4.....	Strong	Cogent, forcible odor.
5.....	Very strong	Intense effect, may bite or irritate.

In this same publication the relation of explosion hazards to readily perceptible concentration of vapors of this kind is defined as follows:

"The warning properties of an explosive gas

or vapor are considered adequate from a practical standpoint if the gas possesses odor intensity degree 2 (faint but readily perceptible) when present in a concentration equal to one-fifth its lower inflammable limit. A safety factor of five used in conjunction with degree 2 permits detection well in advance of a dangerous situation, and at the same time insures a much higher degree of intensity for the immediately dangerous situation. The safety factor is also designed to take care of warning persons less sensitive than the average and to help compensate for fatigue or impairment of the sense of smell."

As will be apparent from the foregoing, if intensity 2 is reached at a lower gas concentration, that is $\frac{1}{20}$ or $\frac{1}{100}$ of the lower explosibility limit, representing safety factors of 20 and 100, respectively, that is definite and positive evidence of over-odorization which is not only an expensive waste of odorant material but is also a nuisance to the gas user, particularly at safety factors of over 100.

This invention comprehends broadly a method and apparatus for increasing the odorization during the first part of the withdrawal of gas from the liquid mixture of odorant and liquefied hydrocarbon gas, for example, in a closed container, and decreasing the degree of odorization during the last part and particularly the gas representing the last 1 or 2 per cent of the liquid that may be withdrawn from such a container. For convenience, the penultimate 1 per cent or that withdrawn when the liquid content of the tank falls from 2 to 1 per cent of the original amount has been chosen to define the nature of this invention, as will be further apparent below.

It is an object of this invention to provide a method and means for obtaining a more uniform odorization of the vapors withdrawn from a closed container of liquefied hydrocarbons, for example propane, butane and the like, which not only prevents under-odorization at the beginning of the withdrawal period and over-odorization at the end of such period but also permits the safe use of a far smaller proportion of odorant in the mixture of liquefied hydrocarbons than has been possible heretofore.

Another object is to provide a method and means of odorizing a gas system to which successive containers of liquefied hydrocarbon gas, for example propane, butane and the like, are connected by the steps of adding less than the customary amount of liquid odorant to the liquefied gas in said containers, imparting added odorant to about the first 20 per cent of

gas vaporized into said system from the liquid in a given container, and abstracting odorant from about the last 20 per cent of gas vaporized from the liquid in said container, the odorant so abstracted being available to be imparted to gas initially withdrawn from the next container of liquefied gas to be connected to the gas system.

Another object is to improve the efficiency of the odorant which is added to a body of liquefied hydrocarbon gases, said odorant being less volatile than said hydrocarbons, so that a lesser amount of odorant is needed to reach a certain degree of odorization of the vapor withdrawn from the mixture by reducing the pressure on said mixture.

These and other objects and advantages of the invention will be further apparent from the following description and from the drawing which illustrates a preferred embodiment of the invention as it is applied to a tank of liquefied hydrocarbon gases.

In the drawing:

Figure 1 is a diagrammatic part sectional view of one form of this invention applied to a system supplied from a tank or bottle of liquefied petroleum gas.

Figure 2 is a chart showing two curves comparing normal odorizing behaviour of liquefied hydrocarbon gas and the effect of this invention upon a quantity of gas to which has been added only about 10 per cent of the normal odorant quantity.

This invention comprehends broadly the use of means in the gas stream or a conduit for the same adapted to withdraw vaporized liquefied hydrocarbons from a succession of closed containers for the latter to which a small proportion of less volatile odorant has been added, these means serving to add or impart odorant to the gas that is first withdrawn from a full tank of the mixture and, more particularly, to withdraw or abstract odorant from the gas which is withdrawn from the last few per cent of the liquid in the almost empty tank. In this example a body of finely divided charcoal or other adsorbent or adsorbent material, such as silica gel, activated alumina or the like, is placed in the outlet conduit system from such a container. In this specification the word adsorbent is used to designate the function and properties of this material, which are not completely understood, and may include absorption, adsorption, or even chemical change. Desirably, but not necessarily, this body is placed in a low pressure zone of the system such as is found between the pressure reducing means or regulator and the gas disposal means, although it is operable in the high pressure zone between the regulator and the closed tank. It is also desirable that the body of adsorbent material be kept in a dry condition, that is, not saturated or wet with the liquefied hydrocarbon in liquid form.

Referring to the drawing and particularly to Figure 1, reference numeral 10 designates a closed tank or container of liquefied hydrocarbons 11 which may be withdrawn through the outlet 12 by opening the valve 13 which may include a pressure regulating means. A conduit 14 leads from the valve 13 through a closed container 15 fitted with retaining means or filters 16 which serve to confine a body of finely divided charcoal or other adsorbent material 17. Liquefied hydrocarbons 11 have previously been odorized by the addition of a small proportion of an odorant material such as the concentrated odorizing ma-

terial prepared from petroleum hydrocarbons and sold by Standard Oil Company of California under the trade-mark "Calodorant." Other types of odorant, so long as they are less volatile than the hydrocarbons 11, may be utilized.

To obtain the best results the adsorbent material 17 in container 15 is precharged with the odorant material. This may be done by withdrawing a quantity of odorized gas through the new material 17 or by saturating that material with a small quantity of liquefied hydrocarbons to which has been added the liquid odorant material. The hydrocarbons are allowed to evaporate freely leaving the odorant material adsorbent or at least retained in the material 17.

Referring to Figure 2, it will be noted that the effect on odor intensity by withdrawal of gases from a mixture of liquefied propane with a small proportion of butane and containing the normal or usual proportion of odorant required by these liquefied hydrocarbons without using this invention is represented by curve A. In the test illustrated the normal proportion of odorant in liquefied hydrocarbons was used, that concentration being required to obtain an initial safety factor of 5 as defined by the United States Bureau of Mines R. I. 2979 quoted above. It will be noted from this curve that the degree of odorization increased steadily from the beginning of the withdrawal period. It will be noted further that the gas representing about the last 20 per cent of liquid, and particularly the penultimate 1 per cent, was extremely over-odorized as evidenced by the high safety factor attained.

Curve B represents the relationship between the amount of liquid withdrawn as gas and the safety factor to attain degree 2 odorization when gas was withdrawn from a closed container of liquefied hydrocarbons containing only about 10 per cent of the amount of "Calodorant" represented by curve A and using this invention. It will be noted that when this invention was used the safety factor at no time fell appreciably below 25, which indicates that an even smaller proportion of liquefied odorant could have been used without falling below the recommended minimum safety factor of 5. Curve B also shows that during the withdrawal of gas representing about the first 20 per cent of the liquid evaporated, odorant was added to the gas by the pre-charged adsorbent material in the gas line. During the withdrawal of gas representing about the last 20 per cent of liquid and particularly the penultimate 1 per cent, the safety factor did not rise above about 60 to 100, the average being about 72, which indicates the advantage of this invention over the prior art.

Although a single example of this method and means for carrying out the invention has been described and illustrated, it will be obvious that it may be applied to other uses and also that numerous modifications and changes may be made without departing from its essential features. In consequence, all such changes that come within the scope of the appended claims are embraced thereby.

I claim:

1. A method of improving the uniformity of odorant concentration in a stream of gas withdrawn from a container charged with a predetermined quantity of liquefied hydrocarbons and a less volatile odorant, which hydrocarbons and odorant will be subject to differential vaporization during said withdrawal whereby the lighter components will be volatilized before the

heavier components thereof, the quantity of said odorant in said container being sufficient to impart acceptable warning properties to said withdrawn gas under conditions which would evaporate said odorant at substantially the same rate as said hydrocarbons, comprising directing said gas stream from the container through a zone having means therein for adding to about the first 20% of gas discharged an amount of odorant sufficient to give acceptable warning properties thereto and for abstracting from about the last 20% of gas withdrawn an amount of odorant sufficient to restore to said means substantially the amount of odorant previously abstracted therefrom by said first withdrawn gas.

2. A method of improving the uniformity of odorant concentration in a stream of gas withdrawn from a container charged with a predetermined quantity of liquefied hydrocarbons and a less volatile odorant, which hydrocarbons and odorant will be subject to differential vaporization during said withdrawal whereby the lighter components will be volatilized before the heavier components thereof, the quantity of said odorant in said container being sufficient to impart acceptable warning properties to said withdrawn gas under conditions which would evaporate said odorant at substantially the same rate as said hydrocarbons, comprising contacting the gas from said container with a body of solid adsorbent material which previously has been charged with odorant whereby the first gas withdrawn from said container is odorized to a degree which is not below the acceptable value, and said adsorbent removes odorant from the last gas withdrawn so that the average safety factor at odor intensity 2 is not over about 60 in the penultimate 1% of gas that can be withdrawn by vaporization from the liquid in said container.

3. A method according to claim 2 in which the safety factor at odor intensity 2 in the penultimate 1% of gas that can be withdrawn by vaporization from the liquid in said container is not materially greater than the minimum safety factor attained during the preceding part of that withdrawal period.

4. A method according to claim 2 in which the safety factor at odor intensity 2 of the penultimate 1% of gas that can be withdrawn by vaporization from the liquid in said container is not over about three times the minimum safety factor attained during the preceding part of that withdrawal period.

5. In combination, a container of liquefied hydrocarbons such as butane, propane and the like to which has been added a predetermined quantity of a less volatile odorant, which hydrocarbons and odorant will be subject to differential vaporization upon reduction of pressure within said container due to withdrawal of gas therefrom whereby the lighter components will be volatilized before the heavier components thereof, the quantity of said odorant in said container being sufficient to impart acceptable warning properties to said withdrawn gas under conditions which would evaporate said odorant at substantially the same rate as said hydrocarbons, an outlet for said container and means in said out-

let for adding to about the first 20% of gas discharged an amount of odorant sufficient to give acceptable warning properties thereto and for abstracting from about the last 20% of gas discharged an amount of odorant sufficient to restore to said means substantially the amount of odorant previously abstracted by said first withdrawn gas.

6. A combination according to claim 5 in which the means in said outlet conduit comprises a solid adsorbent.

7. A combination according to claim 5 in which the means in said outlet conduit comprises a solid adsorbent which previously has been charged with an odorant, said adsorbent being in a dry state.

8. A combination according to claim 5 in which the means in said outlet conduit comprises a dry solid adsorbent selected from the group consisting of charcoal, silica gel and activated alumina.

9. A method of improving the uniformity of odorant concentration in a stream of gas withdrawn from a container charged with a predetermined quantity of liquefied hydrocarbons and a less volatile odorant, which hydrocarbons and odorant will be subject to differential vaporization during said withdrawal whereby the lighter components will be volatilized before the heavier components thereof, the quantity of said odorant in said container being sufficient to impart acceptable warning properties to said withdrawn gas under conditions which would evaporate said odorant at substantially the same rate as said hydrocarbons, comprising contacting the gas from said container with a body of solid adsorbent material which previously has been charged with odorant whereby the first gas withdrawn from said container is odorized to a degree which is not below the acceptable value, and said adsorbent removes odorant from the last gas withdrawn so that the average safety factor at odor intensity 2 is not over about 80 in the penultimate 1% of gas that can be withdrawn by vaporization from the liquid in said container.

10. A method of improving the uniformity of odorant concentration in a stream of gas withdrawn from a container charged with a predetermined quantity of liquefied hydrocarbons and a less volatile odorant, which hydrocarbons and odorant will be subject to differential vaporization during said withdrawal whereby the lighter components will be volatilized before the heavier components thereof, the quantity of said odorant in said container being sufficient to impart acceptable warning properties to said withdrawn gas under conditions which would evaporate said odorant at substantially the same rate as said hydrocarbons, comprising contacting the gas from said container with a body of solid adsorbent material which previously has been charged with odorant whereby the first gas withdrawn from said container is odorized to a degree which is not below the acceptable value, and said adsorbent removes odorant from the last gas withdrawn so that the average safety factor at odor intensity 2 is not over about 100 in the penultimate 1% of gas that can be withdrawn by vaporization from the liquid in said container.
